UNITED STATES PATENT OFFICE.

JOHN W. HODGES, OF WESTPOINT, NEBRASKA.

FLY-TRAP.

1,075,102.

Specification of Letters Patent.

Patented Oct. 7, 1913.

Application filed September 21, 1912. Serial No. 721,612.

To all whom it may concern:

Be it known that I, JOHN W. HODGES, a citizen of the United States, residing at Westpoint, in the county of Cuming and State of Nebraska, have invented certain new and useful Improvements in Fly-Traps, of which the following is a specification, reference being had therein to the accompanying drawing.

10 This invention relates to screen door constructions, and the principal object of the invention is to provide a screen door which is so constructed that it will act as a trap for insects, such as flies.

15 Another object of the invention is to provide an improved type of receptacle in which the flies are caught and killed.

Another object of the invention is to provide an improved means for holding the 20 two sections of the receptacle together and for holding the receptacle in the door frame.

This invention is illustrated in the accompanying drawings, wherein:—

Figure 1 is a front elevation of a door 25 constructed in accordance with this invention. Fig. 2 is a vertical sectional view through the center of the door shown in Fig. 1. Fig. 3 is a perspective view of the receptacle which forms the trap. Fig. 4 is a transverse sectional view of the door. Fig. 5 is a front elevation of the receptacle. Fig. 30 6 is an edge elevation. Fig. 7 is a fragmentary sectional view showing the manner of holding the receptacle in place. Fig. 8 is a fragmentary view showing the manner of holding the two sections of the receptacle in 35 a closed position. Fig. 9 is a perspective view of one of the latches.

Referring to the accompanying drawings 40 it will be seen that this door 10 is provided with upper and lower openings which are covered by wire mesh. The wire mesh 11 which covers the lower opening is placed upon the inner face of the door and is provided with transversely extending corrugations 45 forming pockets 12 extending toward the outer face of the door. These pockets are provided with openings in their upper edges so that any flies which may be in the room may pass out through the openings into the outer air and will be prevented from returning to the room. The fly trap 50 is removably mounted in the upper opening and comprises the two sections 13 and 14 which are hinged together by means of the hinge 15, and which are limited in their

pivotal movement by means of the links 16. This receptacle is of such size that it will fit nicely in the upper opening, and is provided at its outer edge with a beading 17 which forms an abutment to limit the inward movement of the receptacle. A plate 18 is secured to the inner section 14 and extends across a cut-out portion formed in the inner section so that a catch may be 60 connected with the receptacle to hold the same in place. A locking plate 19 is secured to the outer section 13 and passes through the cut-out portion 20 formed in the inner section 14 to hold the sections in 65 a closed position. An opening 21 is formed in the plate 19, and when the receptacle is in/ a closed position, this opening is positioned in alinement with a socket 22 so that a second catch may be passed through the 70 opening 21 into the socket 22 to assist in holding the receptacle in place. Pins 23 are carried by the section 13 and fit into pockets 24 and act as means to prevent vertical movement of the two sections after the 75 sections are in a closed position.

A screen 25 is secured to the section 14 and a second screen 26 is secured to the outer edge of the section 13. This screen 26 is provided at points throughout its height 80 with transversely extending corrugations forming inwardly extending pockets 27. These pockets are provided at their upper edges with a number of openings 28 which permit the flies to enter the receptacle where 85 they are held until it is desired to remove the same. Transversely extending rods 29 are provided to hold the pockets in the proper position and to raise the screen.

When using this device the receptacle is 90 closed and is inserted in the upper opening as shown in Fig. 2. The catches 30 which are pivotally mounted upon the door are then turned so that their lower ends will pass into the socket 22 and beneath the plate 100 18, and the device is ready for use. The flies which alight upon the screen 26 and attempt to enter the room will pass into pockets 27 and through the openings 28 into the interior of the receptacle where they are 105 held until it is desired to remove them. The catches are then turned, and the receptacle removed and the flies can then be killed and removed from the receptacle. These flies may be killed in any desired manner, such 110 for instance as by letting steam pass through the receptacle, or, if desired, the wire screen

may be formed from copper wire and a current of electricity passed through this wire screen so that the flies will be killed by electricity. The receptacle may then be opened 5 and the flies emptied out.

It is noted that, if desired, the catches 30 may be done away with and a plurality of catches 31 pivotally secured to the inner section 14 and turned across the door to hold 10 the receptacle in place. It is preferred, however, to use the catches 30 since as shown in Fig. 8 this type of catch will not only hold the receptacle in the opening but will also hold the sections of the receptacle in a 15 closed position, thus preventing any danger of the receptacle swinging open and thus permitting flies to escape.

Having thus described the invention, what is claimed as new, is:—

- 20 1. A screen door provided with an opening, a receptacle removably mounted in said opening and comprising inner and outer sections hinged together, a locking plate carried by one of said sections and passing 25 through a recess formed in the other of said sections, said plate being provided with a slot registering with a socket in the second section, and catches carried by said door and engaging said receptacle to hold the same in 30 place, one of said catches passing through

the aligned slot and socket to hold the sections of said receptacle in a closed position.

2. A device of the character described comprising a body portion provided with an opening, a receptacle removably mounted in 35 the opening of said body, said receptacle comprising a pair of pivotally connected members, a flange formed upon one of said members for limiting the movement of said device through the opening in said body portion, a plate secured to one of said members and having its free end portion provided with a slot, the other of said members being provided with a recess through which 40 said plate passes and with a socket positioned in alignment with the slot in said plate when said members are in a closed position, and a securing plate pivoted to said body portion, whereby the turning of said plate will cause its free end to be passed 45 through said slot into said pocket for holding said members in a closed position and for holding said device in the opening of said body portion.

In testimony whereof I hereunto affix my 55 signature in presence of two witnesses.

JOHN W. HODGES.
